GOGGLE

Joseph W. Aspenleiter, Rochester, N. Y., assignor
to Bausch & Lomb Optical Company, Rochester,
N. Y., a corporation of New York

Application October 19, 1940, Serial No. 361,939

5 Claims. (Cl. 2—14)

This invention relates to goggles and more particularly it has reference to the bridge member which connects the two eyecups of a goggle.

One of the objects of my invention is to provide an improved bridge member for goggles which will be relatively simple in structure yet efficient in operation. Another object is to provide a goggle having a flexible bridge member which may be readily assembled and adjusted. A further object is to provide a goggle having an adjustable bridge member which also serves to hold the bezel on the eyecup. These and other objects and advantages reside in certain novel features of construction, arrangement and combination of parts as will hereinafter be more fully described and pointed out in the appended claims.

Referring to the drawing:

Fig. 1 is a fragmentary front view of a goggle embodying my invention.

Fig. 2 is a fragmentary side view of same.

Fig. 3 is a fragmentary top plan view of an eyecup.

Fig. 4 is a horizontal sectional view showing the bridge connections with the eyecups.

Fig. 5 is a view of the nasal side of the eyecup and bezel.

Fig. 6 is a fragmentary top plan view of a modification.

Fig. 7 is a horizontal sectional view of the eyecup of Fig. 6.

Fig. 8 is a view taken on line 8—8 of Fig. 7.

A preferred embodiment of my invention is illustrated in the drawing wherein 10 indicates, generally, a goggle having two spaced eyecups 11 which are connected by the flexible bridge member 12. The construction of both eyecups is identical and hence a detailed description of one eyecup will be sufficient. The eyecup 11 is formed so as to fit the contour of the face of the wearer and may be made of any suitable material such as aluminum, molded plastics or the like. A lens 13 rests on the front edge of the eyecup 11 and it is held in place by the bezel 14 which has an overhanging lip or side wall 15. The bezel 14 may also be formed of any suitable material such as metal or molded plastics.

On its temporal side, the bezel 14 is secured to the eyecups by means of a pivotally mounted clasp 16 which engages the upstanding lug 17 carried by the eyecup 11. The clasp 16 is held against accidental opening by the ring 18 attached to the elastic headband 19. The ring 18 passes through an opening, not shown, in the lug 17.

On the nasal side of the eyecup 11, the bezel 14 is held onto the eyecup by means of the flexible strap member 12 which also serves as a bridge for connecting the two eyecups of the goggle. 5 The nasal side of the bezel 14 is provided with a slot 20 while the nasal wall of eyecup 11 is provided with the slot 21 and the notch 22 is formed in the rear face or edge of the eyecup. Both of the slots 20 and 21 and the notch 22 are adjacent each other and in substantial alignment as clearly shown in Fig. 5.

The flexible bridge member 12, which connects the two eyecups 11, may be formed of a strip of leather or other suitable material. As shown in 15 Figs. 1 and 4, the two free ends 23 of strap 12 are located adjacent the front nasal portions of the eyecups. From this position, the strap extends rearwardly and then into the eyecup through the notch 22 and then outwardly through the slot 21 in the eyecup wall. The strap is then looped through the slot 20 in the wall of the bezel 14, is doubled back on itself and again enters the eyecup 11 through slot 21 and then passes out through notch 22 and over to the other eyecup 20 where it is similarly connected, as clearly shown in Fig. 4.

It will be apparent, therefore, that the strap 12 serves to hold the nasal side of the bezel 14 in place on the eyecup and also acts as a bridge member to connect the two eyecups. The bridge member 12 may be readily adjusted so as to vary the pupillary distance between the eyecups in order to fit the face of a wearer. When the two eyecups are moved rearwardly so that the rear faces of the eyecups are brought into contact or in proximity to each other, the parts of the strap 12 are rendered accessible for adjustment purposes. Since the usual buckle member is not required, it is possible to bring the nasal sides of the eyecups into very close proximity so that narrow interpupillary distances may be accommodated.

A modification is shown in Figs. 6—8 wherein 25 indicates an eyecup of a goggle having a different construction. The eyecup 25 may be formed of molded plastic, metal or any other suitable material. The lens 26 is placed against the front edge of the eyecup 25 and held in position by the bezel 27. The temporal side of eyecup 25 has a groove 28 into which is fitted the bead 29 carried by the temporal side of bezel 27. The nasal side of the bezel 27 is held in place by the flexible strap member 30 which also serves as a bridge to connect the two eyecups, both of 55 which are identical in structure.

The nasal side of the bezel 27 is provided with the slot 31 and the nasal wall of the eyecup 25 has the two slots 32 and 33, with slot 33 positioned rearwardly of slot 32. The free ends 34 of strap 30 are positioned between and adjacent the nasal sides of the eyecup 25 and bezel 27. From this position the strap extends rearwardly and into the eyecup through the slot 33 and then out of the eyecup through slot 32. The strap is then looped through the slot 31 in bezel 27, doubled back on itself and extended through slot 32 again and then out through slot 33 and over to the adjacent eyecup, as clearly shown in Fig. 7. The slot 33 should preferably have a substantial width in a direction perpendicular to the plane of the lens 26 in order to afford ample slack in the strap 30 when making adjustments. Such adjustments in bridge length can be readily made and the bridge member 30 may be unloosened when it is desired to remove the bezel 27 to replace the lens.

From the foregoing it will be apparent that I have attained the objects of my invention by providing a goggle having a bridge member which is simple in structure yet efficient in operation. By my novel construction I have eliminated the necessity of using a separate buckle or strap fastening member. My improved bridge can be assembled and adjusted without the use of tools. If the goggle parts are made of molded plastics, for example, the slots and notches would be formed when the parts were molded so that the cost of providing the adjustable bridge member is reduced to a minimum. Various modifications can obviously be made without departing from the spirit of my invention.

I claim:

1. In a goggle the combination of an eyecup having a nasal wall provided with a slot adjacent the front edge of the eyecup, the rear edge of said eyecup having a notch which is substantially in alignment with said slot, and a bridge member secured to said eyecup, said member comprising a flexible strap which is doubled on itself and extends from a point adjacent the outer nasal wall of the eyecup through said slot and into the eyecup and then rearwardly and laterally through said notch to a point outside of the eyecup.

2. A goggle comprising a pair of spaced eyecups, a lens mounted on each eyecup, a bezel for

holding each lens on its eyecup, each eyecup having a slot in its nasal wall, each bezel having a slot in its nasal wall, and a bridge connecting said eyecups, said bridge comprising a flexible strap member which extends through the slot in one eyecup, thence through the slot in the bezel on the eyecup and then through the slot in the eyecup again, whereby the length of said bridge may be selectively adjusted.

3. In a goggle the combination of an eyecup having a slot in its nasal wall and a notch in its rear face, a lens carried on said eyecup, a bezel for holding the lens on the eyecup, said bezel having a slot in its nasal side and a bridge member secured to said eyecup, said member comprising a flexible strap which extends rearwardly from a point adjacent the front of the eyecup through the notch and into the eyecup, thence successively through the slot in the eyecup, the slot in the bezel and the slot in the eyecup and into overlapping relation with the portion of the strap in said notch.

4. A goggle comprising a pair of spaced eyecups, a lens mounted on each eyecup, a bezel for holding each lens on its eyecup, each eyecup having a slot in its nasal wall and a notch in its rear face, each bezel having a slot in its nasal wall, both of said slots and said notch being substantially in alignment, and a bridge connecting said eyecups, said bridge comprising a flexible strap member having a portion reversely looped through the slot in the bezel and thence extending in doubled relation through the first-named slot and into the eyecup and thence through the notch in the rear face of the eyecup whereby the bridge may be selectively adjusted.

5. In a goggle the combination of an eyecup having a groove in its temporal wall and two slots in its nasal wall spaced one in front of the other, a lens carried on the eyecup, a bezel for holding the lens on the eyecup, the temporal side of the bezel having an inwardly projecting bead engaging said groove, the nasal side of said bezel having a slot, and a bridge member connected to said eyecup, said bridge member comprising a flexible strap which is looped through the slot in the bezel, doubled back on itself and then extended through the forward slot in the eyecup and thence out through the rear slot in the eyecup.

JOSEPH W. ASPENLEITER.
